UNITED STATES PATENT OFFICE.

RENÉ GUILLYERY, OF PARIS, FRANCE.

MACHINE FOR TESTING SHEET METAL FOR DRAWING PURPOSES.

Application filed November 28, 1924, Serial No. 752,770, and in France December 18, 1923.

The present invention has for object the testing of sheet metal for drawing purposes.

The test consists in holding the sheet metal to be tested between two circular jaws, 5 and to exert a pressure by means of a ball, at the centre of the sheet metal, and then in observing the moment at which the sheet metal is rent.

The amount the ball has advanced at this moment, that is to say, the drawn concavity which the sheet metal presents, characterizes more or less the drawing properties of the sheet metal.

The machine forming the object of this invention realizes this test simply and easily, it permits the drawn form or cup to be seen at once and it also gives the maximum load at which the metal is rent.

The indication of this maximum load fixes without any possible doubt the moment at which the test should be stopped which if prolonged unnecessarily increases the drawn cup measured.

Figure 1 represents a vertical section of the machine, Figure 2 a plan, Figure 3 the arrangement of the distribution of the pressure, this figure being a vertical section according to line A—A of Fig. 2.

1 is a cast iron frame the top of which carries a cylinder which receives the piston 2 on which a hydraulic pressure is applied. This piston is without packing, so it has no rubbing action; it is terminated by a guide piece 3 which acts on the punch 4 at the end of 35 which is fixed a ball 5 having a diameter of 20 millimeters.

The cover 6 of the cylinder has a nut 7 which supports the bottom jaw 8 against which is pressed during the action the special ring 9 which is worked by means of the 40 hand-lever 10. The piece 11 swings round the axis 12 hinged to let the band of sheet metal to be tested 13 pass. It carries, in the part not hinged, the claws in which the special ring 9 becomes gripped.

The nut 14 with wings 15 is screwed in the piece 11 and carries the top jaws 16, which presses against the ball thrust bearing 34. The top jaw 16 is held pressed 50 against the ball thrust bearing 34 by means of a packing ring 16' placed in a circumferential groove of the nut 14 and taking a bearing on a corresponding annular shoulder of the top jaw 16. A rack 17 fixed to the

guide piece 3 gears with the pinion 18 which 55 works the graduated drum 19 having a spring to take up the play and on which the pointer indicates the movements of the piston that is to say the measurements of the drawn cups.

The very supple cup leather 20 prevents the scale, detached from the sheet metal during the test, falling into the cylinder.

The graduated disc 21 fixed on a micrometer screw 35 the screw always being solicited by the spring 36 which it tends to unscrew, permits the thickness of the sheet metal to be read by the pointer 37.

The bottom of the frame 1 is plugged up by the circular plate 22 and tightened by 70 stud 23 forming a tank for liquid in which is fixed the pressure pump 24, the geared pump is worked from the outside by the crank-hadle 25. This pump 24 sucks in a tank through a pipe (not shown).

The pump delivers the liquid through the pipe 26, provided with a check valve 27, into another pipe 26' extending horizontally (Fig. 3) and leading to a distributor 28 fixed at the bottom of the cylinder by the 80 hollow bolt 29 the pointed screw 30 unscrewed permits the liquid to return to the tank, that is allows the piston to come down. It will be seen that the entire pipe line for the liquid under pressure is contained within the frame 1 of the machine.

The opening 31 permits during the compression the return to the tank of the air which is found above the piston.

The pressure gauge 32 graduated in effective pressures on the piston and carries a maximum hand which permits the load to be followed as increased.

Finally a threaded plug 33 serves to put into the tank the oil for transmission.

Operation.

The operator stands in front of the machine to be able, with his right hand to turn the crank-handle 25 in the same direction 100 as the hands of a watch.

With the left hand, he pushes the hand lever 10 to the end of its stroke to disengage the special shaped ring 9, and with the right hand he lifts the top part with the aid of 105 one of the wings 15 of the nut 14.

He will then put in place the disc or band, to be tested and then, after having replaced

the top part will pull the hand-lever 10 as far as possible to lock the special shaped ring 9.

He screws the winged nut until its is 5 locked.

After having screwed to the bottom the pointed screw 30 and brought the maximum hand of the pressure gauge to zero, he screws back the screw 30 and turns the crank-handle 25 and the pressure increases uniformly.

He follows this increase and, when the movement of the hand slows down, he observes the drawn cup in stopping the test at the moment when the crack is clearly 10 produced.

Without any movement other than to screw the disc 21 to the bottom, the operator can read first, the thickness of the sheet metal, secondly on the graduated drum 19, 20 the drawn cup, and thirdly on the pressure gauge, the maximum pressure exerted by the ball.

After having unscrewed the pointed screw 30 which will allow the piston to come 25 down, and the drum 19 return to zero, he unscrews the wing nut one turn, pushes to the end of its stroke the hand-lever 10, lifts the piece 11 and takes out the sheet metal tested, the machine is then ready for another 30 test.

What I claim as my invention and desire to secure by Letters Patent is:

1. In a machine for testing sheet metal for drawing purposes, a hollow vertical frame, a transverse partition in the said hollow frame for separating a lower tank for the operating liquid and an upper press cylinder, a closure for said tank, a gear pump arranged within the said lower tank, means for actuating this pump from the exterior in order to suck the liquid from the lower tank and to deliver in the upper press cylinder.

2. In a machine for testing sheet metal for drawing purposes, a hollow vertical frame, a transverse partition in the said hollow frame for separating a lower tank for the operating liquid and an upper press cylinder, a closure for said tank, a gear pump arranged within the said lower tank for sucking the liquid therefrom, a delivery pipe, in the said tank, a valve on the said pipe, means for putting it in relation with the upper press cylinder.

3. In a machine for testing sheet metal for drawing purposes, a hollow vertical frame, a transverse partition in the said hollow frame for separating a lower tank for the operating liquid and an upper press cylinder, a closure for said tank, a gear pump arranged within the said lower tank, for sucking the liquid therefrom, a delivery pipe, in the said tank, a valve on the said pipe, a hollow coupling passing through the 60 partition separating the lower tank and the

the upper press cylinder, for putting in relation the delivery pipe of the pump with the press cylinder, means for putting, at will, the upper press cylinder in direct relation with the lower tank.

4. In a machine for testing sheet metal for drawing purposes, a hollow vertical frame, a transverse partition in the said hollow frame for separating a lower tank for the operating liquid and an upper press cylinder, a closure for said tank, a gear pump arranged within the said lower tank, for sucking the liquid therefrom, a delivery pipe, in the said tank, a valve on the said pipe, a hollow coupling passing through the 70 partition separating the lower tank and the upper press cylinder, for putting in relation the delivery pipe of the pump with the press cylinder, a channel in the said hollow coupling opening in the lower tank, a needle screw capable of being operated from the exterior in order to permit of uncovering or obturating the said channel so as to put in relation or not the press cylinder and the lower tank.

5. In a machine for testing sheet metal for drawing purposes, a hollow vertical frame, a transverse partition in the said hollow frame for separating a lower tank for the operating liquid and an upper press cylinder, a closure for said tank, a gear pump arranged within the said lower tank, for sucking the liquid therefrom, a delivery pipe, in the said tank, a valve on the said pipe, a hollow coupling passing through the 80 partition separating the lower tank and the upper press cylinder, for putting in relation the delivery pipe of the pump with the press cylinder, a channel in the said hollow coupling opening in the lower tank, a needle screw capable of being operated from the exterior in order to permit of uncovering or obturating the said channel so as to put in relation or not the press cylinder and the lower tank.

6. In a machine for testing sheet metal for drawing purposes, a hollow vertical frame, a transverse partition in the said hollow frame for separating a lower tank for the operating liquid and an upper press cylinder, a closure for said tank, a gear pump arranged within the said lower tank, for sucking the liquid therefrom, a delivery pipe, in the said tank, a valve on the said pipe, a hollow coupling passing through the 90 partition separating the lower tank and the upper press cylinder, for putting in relation the delivery pipe of the pump with the press cylinder, a channel in the said hollow coupling opening in the lower tank, a needle screw capable of being operated from the exterior in order to permit of uncovering or obturating the said channel so as to put in relation or not the press cylinder and the lower tank.

- exterior in order to permit of uncovering or obturating the said channel so as to put in relation or not the press cylinder and the lower tank, a piston in the press cylinder, a rod on the said piston, a ball at the end of the said rod, a cover for closing the press cylinder, a jaw on the said cover, a pivoting stay, pivoted on the latter, means for securing the said stay in position on the cover. 5
7. In a machine for testing sheet metal for drawing purposes, a hollow vertical frame, a transverse partition in the said hollow frame for separating a lower tank for the operating liquid and an upper press cylinder, a closure for said tank, a gear pump arranged within the said lower tank, for sucking the liquid therefrom, a delivery pipe, in the said tank, a valve on the said pipe, a hollow coupling passing through the partition separating the lower tank and the upper press cylinder, for putting in relation the delivery pipe of the pump with the press cylinder, a channel in the said hollow coupling opening in the lower tank, a needle screw capable of being operated from the exterior in order to permit of uncovering or obturating the said channel so as to put in relation or not the press cylinder and the lower tank, a piston in the press cylinder, a rod on the said piston, a ball at the end of the said rod, a cover for closing the press cylinder, a jaw on the said cover, a pivoting stay, pivoted on the latter, a circular bolt 10 20 25 30 35 40 45 50 55 60 65
- angularly movable on the said cover for permitting to secure thereto the pivoting stay, an inner screw thread in the said stay, a centrally open nut, diametral operating lugs on the said nut in order to screw it in the inner screw thread of the stay, a ball bearing about the bore of the said nut, a jaw bearing on the said ball bearing, a packing ring in the said nut for holding this jaw which applies on the sheet of metal to be tested, means for 70 75 80 85 90 95 100 105 110 115 120 125 130 135
8. In a machine for testing sheet metal for drawing purposes, a hollow vertical frame, a transverse partition in the said hollow frame for separating a lower tank for the operating liquid and an upper press cylinder, a closure for said tank, a gear pump arranged within the said lower tank, for sucking the liquid therefrom, a delivery pipe, in the said tank, a valve on the said pipe, a hollow coupling passing through the partition separating the lower tank and the upper press cylinder, for putting in relation the delivery pipe of the pump with the press cylinder, a channel in the said hollow coupling opening in the lower tank, a needle screw capable of being operated from the exterior in order to permit of uncovering or obturating the said channel so as to put in relation or not the press cylinder and the lower tank, a piston in the press cylinder, a rod on the said piston, a ball at the end of the said rod, a cover for closing the press cylinder, a jaw on the said cover, a pivoting stay, pivoted on the latter, a circular bolt 10 20 25 30 35 40 45 50 55 60 65
- angularly movable on the said cover for permitting to secure thereto the pivoting stay, an inner screw thread in the said stay, a centrally open nut, diametral operating lugs on the said nut in order to screw it in the inner screw thread of the stay, a ball bearing about the bore of the said nut, a jaw bearing on the said ball bearing, a packing ring in the said nut for holding this jaw which applies on the sheet of metal to be tested, means for 70 75 80 85 90 95 100 105 110 115 120 125 130 135
10. In a machine for testing sheet metal for drawing purposes, a hollow vertical frame, a transverse partition in the said hollow frame for separating a lower tank for the operating liquid and an upper press cylinder, a closure for said tank, a gear pump arranged within the said lower tank, for sucking the liquid therefrom, a delivery pipe, in the said tank, a valve on the said pipe, a hollow coupling passing through the partition separating the lower tank and the upper press cylinder, for putting in relation the delivery pipe of the pump with the press cylinder, a channel in the said hollow coupling opening in the lower tank, a needle screw capable of being operated from the exterior in order to permit of uncovering or obturating the said channel so as to put in relation or not the press cylinder and the lower tank, a piston in the press cylinder, a rod on the said piston, a ball at the end of the said rod, a cover for closing the press cylinder, a jaw on the said cover, a pivoting stay, pivoted on the latter, a circular bolt 10 20 25 30 35 40 45 50 55 60 65
- angularly movable on the said cover for permitting to secure thereto the pivoting stay, an inner screw thread in the said stay, a centrally open nut, diametral operating lugs on the said nut in order to screw it in the inner screw thread of the stay, a ball bearing about the bore of the said nut, a jaw bearing on the said ball bearing, a packing ring in the said nut for holding this jaw which applies on the sheet of metal to be tested, means for 70 75 80 85 90 95 100 105 110 115 120 125 130 135

- stay, pivoted on the latter, a circular bolt angularly movable on the said cover for permitting to secure thereto the pivoting stay, an inner screw thread in the said stay, a centrally open nut, diametral operating lugs on the said nut in order to screw it in the inner screw thread of the stay, a ball bearing about the bore of the said nut, a jaw bearing on the said ball bearing, a packing ring in the said nut for holding this jaw which applies on the sheet of metal to be tested, a vertical screw, passing through one of the operating lugs of the nut and taking a bearing on the upper face of the stay, a graduated dial rigid with the said screw, a fixed index on the nut, a spring acting by torsion on the said screw for automatically bringing it back to its position of rest.
11. In a machine for testing sheet metal for drawing purposes, a hollow vertical frame, a transverse partition in the said hollow for separating a lower tank for the operating liquid and an upper press cylinder, a closure for said tank, a gear pump arranged within the said lower tank, for sucking the liquid therefrom, a delivery pipe, in the said tank, a valve on the said pipe, a hollow coupling passing through the partition separating the lower tank and the upper press cylinder, for putting in relation the delivery pipe of the pump with the press cylinder, a channel in the said hollow coupling opening in the lower tank, a needle screw capable of being operated from the exterior in order to permit of uncovering or obturating the said channel so as to put in relation or not the press cylinder and the lower tank, a piston in the press cylinder, a rod on the said piston, a ball at the end of the said rod, a cover for closing the press cylinder, a jaw on the said cover, a pivoting stay, pivoted on the latter, a circular bolt angularly movable on the said cover for permitting to secure thereto the pivoting stay, an inner screw thread in the said stay, a centrally open nut, diametral operating lugs on the said nut in order to screw it in the inner screw thread of the stay, a ball bearing about the bore of the said nut, a jaw bearing on the said ball bearing, a packing ring in the said nut for holding this jaw which applies on the sheet of metal to be tested, a vertical screw, passing through one of the operating lugs of the nut and taking a bearing on the upper face of the stay, a graduated dial rigid with the said screw, a fixed index on the nut, a spring acting by torsion on the said screw for automatically bringing it back to its position of rest, a rack on the piston rod, a pinion cooperating with the said rack, a graduated drum mounted on the axis of the said pinion, externally to the frame of the machine, a fixed index on the said frame, a spring acting by torsion for bringing back the graduated drum to its position of rest.
12. In a machine for testing sheet metal for drawing purposes, a hollow vertical frame, a transverse partition in the said hollow for separating a lower tank for the op-

erating liquid and an upper press cylinder, a closure for said tank, a gear pump arranged within the said lower tank, for sucking the liquid therefrom, a delivery pipe, in the said tank, a valve on the said pipe, a hollow coupling passing through the partition separating the lower tank and the upper press cylinder, for putting in relation the delivery pipe of the pump with the press cylinder, a channel in the said hollow coupling opening in the lower tank, a needle screw capable of being operated from the exterior in order to permit of uncovering or obturating the said channel so as to put in relation or not the press cylinder and the lower tank, a piston in the press cylinder, a rod on the said piston, a ball at the end of the said rod, a cover for closing the press cylinder, a jaw on the said cover, a pivoting stay, pivoted on the latter, a circular bolt angularly movable on the said cover for permitting to secure thereto the pivoting stay, an inner screw thread in the said stay, a centrally open nut, diametral operating lugs on the said nut in order to screw it in the inner screw thread of the stay, a ball bearing about the bore of the said nut, a jaw bearing on the said ball bearing, a packing ring in the said nut for holding this jaw which applies on the sheet of metal to be tested, a vertical screw, passing through one of the operating lugs of the nut and taking a bearing on the upper face of the stay, a graduated dial rigid with the said screw, a fixed index on the nut, a spring acting by torsion on the said screw for automatically bringing it back to its position of rest, a rack on the piston rod, a pinion cooperating with the said rack, a graduated drum mounted on the axis of the said pinion, externally to the frame of the machine, a fixed index on the said frame, a spring acting by torsion for bringing back the graduated drum to its position of rest.

13. In a machine for testing sheet metal for drawing purposes, a hollow vertical frame, a transverse partition in the said hollow for separating a lower tank for the operating liquid and an upper press cylinder, a closure for said tank, a gear pump arranged within the said lower tank, for sucking the liquid therefrom, a delivery pipe, in the said tank, a valve on the said pipe, a hollow coupling passing through the partition separating the lower tank and the upper press cylinder, for putting in relation the delivery pipe of the pump with the press cylinder, a channel in the said hollow coupling opening in the lower tank, a needle screw capable of being operated from the exterior in order to permit of uncovering or obturating the said channel so as to put in relation or not the press cylinder and the lower tank, a piston in the press cylinder, a rod on the said piston, a ball at the end of the said rod, a cover for closing the press cylinder, a jaw on the said cover, a pivoting stay, pivoted on the latter, a circular bolt angularly movable on the said cover for permitting to secure thereto the pivoting stay, an inner screw thread in the said stay, a centrally open nut, diametral operating lugs on the said nut in order to screw it in the inner screw thread of the stay, a ball bearing about the bore of the said nut, a jaw bearing on the said ball bearing, a packing ring in the said nut for holding this jaw which applies on the sheet of metal to be tested, a vertical screw, passing through one of the operating lugs of the nut and taking a bearing on the upper face of the stay, a graduated dial rigid with the said screw, a fixed index on the nut, a spring acting by torsion on the said screw for automatically bringing it back to its position of rest, means for measuring the rectilinear displacements of the press piston and of the ball.
14. In a machine for testing sheet metal for drawing purposes, a hollow vertical frame, a transverse partition in the said hollow for separating a lower tank for the op-

of the said rod, a cover for closing the press cylinder, a jaw on the said cover, a pivoting stay, pivoted on the latter, a circular bolt angularly movable on the said cover for permitting to secure thereto the pivoting stay, 5 an inner screw thread in the said stay, a centrally open nut, diametral operating lugs on the said nut in order to screw it in the inner screw thread of the stay, a ball bearing about the bore of the said nut, a jaw bearing on the said ball bearing, a packing ring in the said nut for holding this jaw which applies on the sheet of metal to be tested, 10 a vertical screw, passing through one of the operating lugs of the nut and taking a bearing on the upper face of the stay, a graduated dial rigid with the said

screw, a fixed index on the nut, a spring acting by torsion on the said screw for automatically bringing it back to its position of rest, 20 a rack on the piston rod, a pinion cooperating with the said rack, a graduated drum mounted on the axis of the said pinion, externally to the frame of the machine, a fixed index on the said frame, a spring acting by torsion for bringing back the graduated drum to its position of rest, a pressure gauge communicating with the press cylinder for indicating the pressure at the 25 time of breakage of the sheet of metal subjected to the test.

30

In testimony whereof I have signed my name to this specification.

RENÉ GUILLERY.
